UNITED STATES PATENT OFFICE.

JAMES PLATT, OF UTICA, NEW YORK.

IMPROVED WATER-WHEEL.

Specification forming part of Letters Patent No. **39,834**, dated September 8, 1863; antedated July 20, 1862.

To all whom it may concern:

Be it known that I, JAMES PLATT, of Utica, in the county of Oneida and State of New York, have invented a new and Improved Water-Wheel; and I do hereby declare that the following is a full, clear, and exact description of the same, reference being had to the accompanying drawings, making a part of this specification, in which—

Figure 1 is a plan or top view of my invention; Fig. 2, a vertical section of the same, taken in the line *x x*, Figs. 1 and 3; Fig. 3, a horizontal section of the same, taken in the line *y y*, Fig. 2; Fig. 4, a vertical section of a portion of the same, taken in the line *z z*, Fig. 3.

Similar letters of reference indicate corresponding parts in the several figures.

To enable those skilled in the art to fully understand and construct my invention, I will proceed to describe it.

A represents the wheel-shaft, the lower end of which is stepped in the lower part of a suitable framing, *B*, as shown at *a*, and the upper part fitted in a bearing, *b*, at the upper part of said framing.

To the lower part of the shaft *A* the wheel *C* is attached. This wheel may be described as being formed of an annular box composed of two parts, *c d*. The part *c* is the portion that is attached to the shaft *A*, and said part comprises the bottom and outer side of the wheel, as shown at *1 2*, Fig. 2, the bottom *1* being provided with or connected to radial arms *3*, which project from a hub, *4*, that is fitted on shaft *A* and secured thereto by a setscrew, *5*. The other portion, *d* of the wheel is composed of the top *6* and the inner side, *7*, the latter extending down to a semicircular rim, *e*, which is attached to arms *f*, that project from a hub, *g*, through which the shaft *A* passes loosely.

D is a box or chute, of sector form, which is attached to the rim *e*, the outer edge of the former coinciding with the latter. (See Fig. 3.) Between the box or chute *D* and the end of the rim *e* there is a space or opening, *h*, which serves as the eduction or discharge opening for the wheel. The box or chute *D* is the induction-passage, and it has a pipe or tube, *E*, attached, which is provided with a gate, *F*. (See Fig. 2.) The upper edge of the outer side, *2*, of the wheel is provided with a hori-

zontal flange, *i*, and the top plate, *6*, of the wheel projects over said flange *i* and is secured thereto by bolts or screws *j*. The lower edge of the inner side, *7*, of the wheel fits on the rim *e* and within a circular flange, *k*, so as to make a joint as near water-tight as may be without producing much friction. (See Fig. 2.) To the edge of the box or chute *D*, or rather at one side of its orifice, there is secured a segment, *G*, which is fitted within the wheel *C*, and has a permanent position therein. This segment serves as a partition or abutment within the wheel, (see Fig. 3,) and its use will be presently shown.

H represent the buckets, which are fitted within the wheel at opposite sides of its center or shaft. These buckets are attached at their outer ends to shafts *ll*, which are fitted vertically in recesses *mm*, at the outer side of the wheel. The buckets are allowed to swing from their shafts *ll* as centers and extend entirely across the wheel when acted upon by the water, or be withdrawn or swing within their recesses *mm* when in an open state, so as to leave the inner surface of the side *2* perfectly free or unobstructed. (See Fig. 3, in which both positions of the buckets are shown.) The upper ends of the shafts *ll* are each provided with an arm, *n*, which have friction-rollers *o o* at their ends. These friction-rollers *o o* work within a stationary-cam, *I*, which is secured to the framing *A* directly above the wheel *C*. One portion, *p*, of the cam is a semi-circle and formed of a single rim, while the other portion, *q*, may be described as being of the form of a semi-ellipse, and composed of two concentric rims, *8 8*, as shown clearly in Fig. 1.

The operation of the wheel is as follows: When the gate *F* is open, the water passes through the pipe or tube *E* into the box or chute *D*, and from thence into the wheel *C*, and acts against the bucket *H*, which extends across the wheel, the partition or abutment *G* preventing the water from moving in an opposite direction. (See Fig. 3.) The bucket *H* is kept across the wheel by the part *p* of the cam *I*, the roller *o* of the arm *n* of said bucket being within the part *p*, and when said bucket reaches the opening *h* it is thrown open by the part *q* of the cam, the roller *o* working or passing between the rims *8 8*. As one bucket opens the other closes or is ex-

tended across the wheel by the part *p* of the cam. The buckets, it will be seen, are allowed to pass the partition or abutment *G*, in consequence of being within the recesses *m* when passing the abutment.

By this invention it will be seen that after the effective force of the water has expended itself against or upon the buckets it is discharged, the water passing about half way round the wheel. The water, therefore, cannot serve as a drag or drawback, as would be the case if it passed entirely around the wheel, for the water is discharged from the wheel before the velocity of the former is appreciably diminished.

I would remark that this wheel might be placed and run in a vertical position, but a horizontal position would be preferable.

Having thus described my invention, what I claim as new, and desire to secure by Letters Patent, is—

The arrangement of the pivoted buckets *H H*, recesses *m m*, and segment *G* with the wheel *C*, hubs *4 g*, arms *f*, and inclined sector-chute *D*, all in the manner herein shown and described.

JAMES PLATT.
